UNITED STATES PATENT OFFICE.

REUBEN R. ROW, OF JERSEY CITY, NEW JERSEY, ASSIGNOR TO THE JAMES REILLY REPAIR AND SUPPLY COMPANY, OF JERSEY CITY, NEW JERSEY, A CORPORATION OF NEW JERSEY.

MEANS FOR COILING PIPES OR TUBES.

No. 865,803.

Specification of Letters Patent.

Patented Sept. 10, 1907.

Application filed July 20, 1906. Serial No. 326,980.

To all whom it may concern:

Be it known that I, REUBEN R. Row, a citizen of the United States, and a resident of Jersey City, in the county of Hudson and State of New Jersey, have invented certain new and useful Improvements in Means for Coiling Pipes or Tubes, of which the following is a specification.

The invention relates to improvements in means for forming pipe-coils of the character used in feed water heaters, condensers, evaporators and other apparatus; and it consists in the novel features, arrangements and combinations of parts hereinafter described, and particularly pointed out in the claims.

The object of the invention is to produce novel means for rapidly, accurately and automatically fashioning a length of straight pipe or tubing into a uniform spiral coil, without flattening the pipe and without necessitating the filling of the pipe, preparatory to the coiling operation, with a solid substance to prevent such flattening.

It has heretofore been necessary in the formation of spiral coils of copper tubing to solidly fill the straight length of tubing preparatory to coiling the same, and this process has not only involved considerable annoyance, uncertainty and expense in preparing the tubes but added labor and expense in thereafter removing the filling from the coil.

One of the purposes of my invention is to provide means adapted to coil straight tubes without the same being filled and thus to avoid the labor and expense heretofore incurred in filling the straight tubes and then clearing out the coils.

In carrying out my invention I mount in a lathe a spirally grooved mandrel around which the tube or pipe is coiled and provide on the traveling carriage of the lathe a coiling die or tool for coöperation with said mandrel in compelling the tube to become accurately and uniformly coiled upon the same. I also provide the coiling die or tool with means, which may be brought into use when desired, for forming a groove in the tube as coiled, said groove extending the full length of the tube and being desirable in coils for evaporators and some other apparatus.

The invention will be more fully understood from the detailed description hereinafter presented, reference being had to the accompanying drawings, in which:

Figure 1 is a front view, partly broken away, of a lathe equipped with a mandrel and coiling-die embodying my invention, the mandrel being partly broken away and shown with a tube coiled thereon; Fig. 2 is a top view of same, the dotted lines at the right hand portion of the figure indicating the manner of bending the end of the tube straight and in line with the length of the coil to be formed before the coiling

operation is carried out; Fig. 3 is a transverse section 55 through the mandrel on the dotted line 3—3 of Fig. 2, the rear portion of the coiling die being also shown in section to disclose the roller adjustably held therein for grooving the tube as coiled, when desired; Fig. 4 is a detached top view of the coiling die to be secured on 60 the traveling carriage of the lathe; Fig. 5 is a horizontal section through the mandrel and die on the dotted line 5—5 of Fig. 3 and showing the groove-forming roller as having been advanced to produce a groove in the tube as coiled; and Fig. 6 is a vertical section through the 65 coiling die on the dotted line 6—6 of Fig. 3, the mandrel being omitted.

In the drawings, 10, 10 respectively designate portions of the head and tail stocks of a known form of lathe; and 11 denotes a portion of the usual carriage 70 which during the operation of the lathe is caused to travel lengthwise of same between the vertical planes of said head and tail stocks.

The spirally grooved mandrel is designated by the numeral 12, and it is mounted between the head and 75 tail stocks of the lathe above the carriage 11, upon which I detachably secure, by means of bolts 13, the coiling die or tool 14. The mandrel 12 is formed with a continuous spiral groove 15 adapted to the diameter of the tube to be coiled, and at its left hand end this 80 mandrel is clamped to the head stock and derives its rotary motion therefrom. At its right hand end the mandrel 12 is formed with a plain shank-portion 16 having a transverse aperture 17 to receive the stem 18 of a hook-block 19, the latter engaging the surface of 85 said shank-portion 16 (Fig. 1) and being detachably secured in place by means of a cotter-key 20 which is passed through a slot in the stem 18 close to said shank-portion 16. At its inner end the hook-block 19 is grooved to receive and hold the end portion of the 90 tube, numbered 21, against the mandrel, as shown in Figs. 1 and 2, preparatory to the formation of the coil and also to the bending of a definite length, numbered 22, of the end of the tube 21 from its initial position shown by dotted lines in Fig. 2, to a position in line 95 with the length of the mandrel and against the side of the block 19, as shown by solid lines in Figs. 1 and 2, the forward edge of the groove in the block being convexed, as denoted by dotted lines in Fig. 2, to avoid the bending of the end 22 around a sharp angle. The 100 block 19 thus operates as a grip for holding down the forward end of the tube upon the mandrel and as an anvil for enabling the proper bending of the end 22 of the tube at substantially right angles to its initial position. The end 22 of the tube is bent into the 105 form shown for two reasons, one being that such end is required for connecting the coil with the usual header with which it coöperates in the condenser, heater or

other apparatus, and the other being that such end enables the block 19 to very firmly hold the end of the tube rigidly on the mandrel while the latter is rotating toward the front for compelling the tube to coil into the 5 groove thereof.

The coiling die or tool 14 comprises a forwardly projecting table-portion 23 (Figs. 3 and 4) having a feed groove 24, and an upwardly extending rear portion 25, whose operating face is on the arc of a circle and formed 10 with a groove 26 and convex rib 27, said groove 26 being a continuation of the groove 24 and set at the same pitch as the groove in the mandrel 12, and said convex rib 27 being elongated and on the arc of a circle and set at 15 the same pitch as the groove in said mandrel. The rib 27 is parallel with and adjacent to the groove 26, as clearly shown in Fig. 4. At opposite sides of the groove 26 are shoulders 28, 29 respectively and at the outer side of the rib 27 is a shoulder 30, all of these shoulders being parallel with each other and on the arc of a circle 20 and on the same pitch as the spiral rib 31 defining the groove 15 in the mandrel 12.

When the tool 14 is set up close against the mandrel 12, as shown in Figs. 3 and 5, the spiral rib 31 of the mandrel fits against the shoulders 28, 29, 30 of said tool 25 and the rib 27 of said tool fits within and engages the wall of a section of the groove 15 of said mandrel, while the groove 26 of said tool matches a section of said groove 15 and therewith defines a passage, circular in cross-section, through which the tube is drawn during the coiling 30 operation, said passage in all cases being of a size adapted to the diameter of the tube to be coiled.

In the upwardly extending rear portion 25 of the tool 14 is mounted a threaded screw 32 having on its outer end a handle 33 and at its inner end a fork 34 carrying 35 a roller 35, which may be set forwardly, when desired, to lie, at a peripheral edge, in the path of the tube drawn through the groove 26, as shown in Figs. 5 and 6, so that it may during the coiling of the tube form a concave groove 36 therein, the groove 36 being desirable 40 when the coil is to be employed in some forms of evaporators. When it is not desired to form the groove 36 in the tube as coiled, the wheel 35 will be held in a rear position beyond the groove 26 by means of the adjusting screw 32, said wheel at such time performing no 45 function.

In the employment of the invention, the mandrel 12 will be secured between the head and tail stocks 10 and the tool 14 mounted upon the carriage 11, which will initially be adjacent to the right hand end of the mandrel. The straight tube to be coiled will be inserted 50 endwise below the right hand end of the mandrel and set within the end portion of the groove 15 thereof, the end of said tube being then carried upwardly along the rear side of the mandrel and then forwardly to the position shown by dotted lines in Fig. 2, whereupon the end portion 22 of said tube will be bent along the side of the block 19, as shown by solid lines in Fig. 2. The tool 14 will then be drawn forwardly on the carriage toward and against the mandrel and the tube then on 55 the end of the same, and rigidly secured by bolts 13 against endwise movement, the grooves 24, 26 of said tool fitting upon the tube and the rib 27 on said tool entering the groove 15 of the mandrel immediately in advance of that portion of the tube housed by said groove 26. The mandrel, tube and tool being thus po-

sitioned, power will be applied through the head-stock to rotate the mandrel upwardly and toward the front, with the result that the tube will be gradually drawn into the groove 15 of and coiled upon the mandrel and the tool 14 and carriage 11 will gradually travel toward the left hand end of the mandrel, the engagement of the rib 27 on the tool with the walls of the groove of the rotating mandrel compelling the tool to travel along the mandrel at just the same rate of speed as the tube is drawn through the groove 26 and coiled upon the mandrel. During the coiling of the tube, the latter is drawn through the passage formed by the matched grooves 15, 26 and is closely confined therein, whereby said tube is prevented from flattening or becoming otherwise distorted. The rib 27 on the tool not only enables the rotating mandrel to compel the travel of the tool but said rib assures the due relation of the groove 26 with the groove of the mandrel, whereby a uniform coil is produced and the coiling operation rendered entirely successful. When it is desired to groove the coil 80 as formed, as shown in Fig. 5, the roller 35 will be adjusted forwardly so that the tube on its passage through the groove 26 will be forced to move against it. After the tube has once been applied upon the end of the mandrel and the tool 14 adjusted forwardly against the 90 same and the mandrel, the coiling operation proceeds automatically and with proper rapidity.

By means of my invention I am enabled to form the coils without first solidly filling the tubes which is a matter of considerable importance.

The bending of the end portions of the tubes is an operation carried on independently of the tool 14, and in order to avoid the flattening of the tube during such operation I fill said portions solidly with rosin or other suitable material which may be removed (as by melting 100 the rosin) after the coiling operation has been concluded.

What I claim as my invention and desire to secure by Letters-Patent, is:

1. A pipe-coiling mechanism comprising a spirally grooved mandrel, means for rotating the same, a coiling tool adapted to said mandrel, and a traveling carriage for said tool, said tool having a face on the arc of a circle encompassing a portion of said mandrel and possessing a groove matching and extending along a section of the 110 groove in the mandrel and a part entering and engaging the wall of another section thereof; substantially as set forth.

2. A pipe-coiling and grooving mechanism comprising a spirally grooved mandrel, means for rotating the same, a 115 coiling tool adapted to said mandrel and having means to groove the pipe as coiled, and a traveling carriage for said tool, said tool having a face on the arc of a circle encompassing a portion of said mandrel and possessing a groove matching and extending along a section of the groove in 120 the mandrel and a part entering and engaging the wall of another section thereof; substantially as set forth.

3. A pipe-coiling and grooving mechanism comprising a spirally grooved mandrel, means for rotating the same, a coiling tool adapted to said mandrel and having a device to 125 groove the pipe as coiled, adjusting means for said device, and a traveling carriage for said tool, said tool having a face on the arc of a circle encompassing a portion of said mandrel and possessing a groove matching and extending along a section of the groove in the mandrel and a part 130 entering and engaging the wall of another section thereof; substantially as set forth.

4. A pipe-coiling mechanism comprising a spirally grooved mandrel, means for rotating the same, a coiling tool, and a carriage for said tool, said tool comprising a 135 forwardly projecting table portion and an upwardly ex-

- tending rear portion adapted to said mandrel and formed with communicating grooves in said portions to receive the pipe and with a rib to enter and engage the wall of the groove in the mandrel; substantially as set forth.
5. A pipe-coiling mechanism comprising a spirally grooved mandrel having a spiral rib defining the groove, means for rotating the same, a coiling tool, and a carriage for said tool, said tool comprising a forwardly projecting table portion and an upwardly extending rear portion adapted to said mandrel and formed with communicating grooves in said portions to receive the pipe, a rib to enter and engage the wall of the groove in the mandrel and parallel shoulders on the arc of a circle to engage the rib on the mandrel; substantially as set forth.
10. A pipe-coiling and grooving mechanism comprising a spirally grooved mandrel, means for rotating the same, a coiling tool, a roller carried by said tool for grooving the pipe as coiled, and a carriage for said tool, said tool comprising a forwardly projecting table portion and an upwardly extending rear portion adapted to said mandrel and formed with communicating grooves in said portions to receive the pipe and with a rib to enter and engage the wall of the groove in the mandrel; substantially as set forth.
15. A pipe-coiling and grooving mechanism comprising a spirally grooved mandrel, means for rotating the same, a coiling tool, a roller carried by said tool for grooving the pipe as coiled, and a carriage for said tool, said tool comprising a forwardly projecting table portion and an upwardly extending rear portion adapted to said mandrel and formed with communicating grooves in said portions to receive the pipe and with a rib to enter and engage the wall of the groove in the mandrel; substantially as set forth.
20. A pipe-coiling mechanism comprising a spirally grooved mandrel, means for securing the end of a length of pipe thereto, means for rotating the mandrel, a coiling tool adapted to said mandrel, and a traveling carriage for said tool, said tool having a face on the arc of a circle encompassing a portion of said mandrel and possessing a groove matching and extending along a section of the groove in said mandrel and an elongated rib encircling a portion of said mandrel and entering and engaging the wall of another section of the groove thereof; substantially as set forth.
25. A pipe-coiling mechanism comprising a spirally grooved mandrel, means for securing the end of a length of pipe thereto, means for rotating the mandrel, a coiling tool adapted to said mandrel, and a traveling carriage for said tool, said tool having a face on the arc of a circle encompassing a portion of said mandrel and possessing a groove matching and extending along a section of the groove in said mandrel and an elongated rib encircling a portion of said mandrel and entering and engaging the wall of another section of the groove thereof; substantially as set forth.
30. A pipe-coiling and grooving mechanism comprising a spirally grooved mandrel, means for securing the end of a length of pipe thereto, means for rotating the mandrel, a coiling tool adapted to said mandrel, and a traveling carriage for said tool, said tool having a face on the arc of a circle encompassing a portion of said mandrel and possessing a groove matching and extending along a section of the groove in said mandrel and an elongated rib encircling a portion of said mandrel and entering and engaging the wall of another section of the groove thereof; substantially as set forth.
